UNITED STATES PATENT OFFICE

2,198,646

ELECTRIC CONNECTOR

Frank E. Wolcott, West Hartford, Conn., assignor
to The Silex Company, a corporation of Connecticut

Original application July 10, 1935, Serial No.
30,647. Divided and this application August 24,
1938, Serial No. 226,599

8 Claims. (Cl. 219—19)

My invention relates to electric connectors. It has among its objects to provide an improved electric connector, and, more particularly, such means especially adapted to use in connection with electric heating devices of the type described and claimed in my copending application Serial No. 30,647, filed July 10, 1935, of which this application is a division. A further object of my invention is to provide an improved connector adapted to connect a heating unit to a suitable base and whereby, when the latter and the connecting means are disposed above the heating unit in the path of the heat rising therefrom, it is made possible to eliminate the breaking down and sticking of the electrical contact members, heretofore experienced. A still further object of my invention is to provide such improved electrical connector means comprising improved contacts and also connected and arranged in an improved manner and having improved connecting and releasing means operable from the top of the support from which the heating element depends. These and other objects and advantages of my improved construction will, however, hereinafter more fully appear.

In the accompanying drawing, I have shown for purposes of illustration one embodiment which my invention may assume in practice.

In the drawing:

30 Figure 1 is a side elevation, partially in section, of this form of my improved construction mounted in depending relation on a suitable support;

35 Fig. 2 is an enlarged sectional view taken at right angles to the section in Figure 1;

Fig. 3 is a bottom plan view on line 3—3 of Figure 2 of the upper insulating support, the heating unit being removed;

40 Fig. 4 is a top plan view on line 4—4 of Figure 2, of the heating unit when separated from its upper insulating support, and

Fig. 5 is a bottom plan view of the heating unit.

In this illustrative construction, I have shown 45 my improved connector means as acting to connect a suitable insulating base 1 carried by any suitable support 2, with a depending vertically disposed heating unit 3; the connecting means between the insulating member 1 and heating 50 unit 3 being of an improved construction, as hereinafter described.

Herein, an insulating member 1 of generally round or disc form is suitably connected, as by vertically disposed screws 4, to the support 2, the 55 screws 4 being disposed on opposite sides of the

vertical axis of the member 1 and in parallel relation and having upper slotted ends 5 accessible from above the support, and their lower threaded ends carrying nuts 6 received in suitable corresponding recesses 7 in the under surface of the member 1. Preferably, also, an insulating washer 8 is provided between the member 1 and the support 2 and the screws 4 are also passed through this washer, while a metal washer 9 is disposed coaxially with the member 1 and between the insulating washer 8 and the support 2. Here it will be also noted that at right angles to the screws 4, and also on opposite sides of the axis of the member 1, vertical contact carrying screws 10 are provided in the member 1, as shown in Figure 2. These screws 10 herein are oppositely disposed with respect to the screws 4 and are threaded at their upper ends into nuts 11 in suitable corresponding recesses 12 in the top of the insulating member 1 and beneath the insulating washer 8. Also, they have their shanks extending downward through apertures 13, while their lower headed ends carry hollow, internally round and tapered, externally hexagonal, integral socket sleeves or members 14 of truncated conical form, each disposed in slightly larger corresponding chambers 15 opening out through the bottom of the member 1, from which bottom the lower ends of the socket members 14 protrude slightly in the illustrative construction. Herein, the shanks of the screws 13 extend through suitable apertures 16 in the tops of the socket members 14, and slotted heads 17 are provided on the lower ends of these shanks. Thus, when these slotted heads are rotated, the socket members 14 are pressed upward to press conductors 18, 18a between the upper ends of the socket members 14 and washers 19 disposed coaxially on the screws 10. As shown, suitable grooves 20 are also provided in the under face of the insulating member 1 to permit the passage of the conductors 18, 18a to the binding posts thus provided, while these conductors are effectually insulated from one another and the screws 4 by their disposition in these grooves 20. Attention here is further directed to the fact that the insulating member 1, insulating washer 8 and metal washer 9 are provided with registering apertures adapted to provide an axial passage 21 in which is disposed the upper threaded end of an adjusting screw 22 connected to and operative to move the heating unit 3 axially, as hereinafter described, an adjusting and holding nut 23 in engagement with the upper surface of the support, herein being threaded on the extremity of this screw which

extends upwardly beyond that surface of the support 2.

Referring to the heating unit 3, it will be noted that the same includes a generally cylindrical body of insulating material disposed in spaced relation vertically below the insulating member 1, and that the lower end of the adjusting screw 22 is extended through an axial passage 24 in the top of this body; this screw being

10 provided on its lower end with a head 25 received in a correspondingly shaped recess 26 in the top of an axial chamber 27 in the member 3, while a lock nut 28 is provided on and near the bottom of the threaded portion of the adjusting screw and disposed in a corresponding recess 29 in the top of the member 3. Improved connector contact means are also provided on the top of the insulating body of the heating unit 3, which are adapted to cooperate with the connect-
15 or sockets 14 on the upper insulating base 1 and to be moved into and out of operative relation to these sockets upon operation of the adjusting nut 23. These contact means herein include hollow, externally tapered and internally cylind-
20 rical and threaded integral truncated sleeves or members 30 having on one end external tapered surfaces of round cross section engageable with the like internal tapered surfaces of the sockets 14 and hexagonal opposite ends in suit-
25 able slightly larger recesses 31 in the top of the body of the member 3. As shown, the upper ends of threaded connecting screws 32 are threaded into the lower ends of these members 30 and extend downward therefrom with their
30 grooved heads 33 accessible from the top of a hollow portion or chamber 27 in the heating unit. One of the screws 32 also has its head form a binding screw for an end portion 34 of a resist-
35 ance element 35 wound on the outer surface of the heating unit 3 around this chamber, while the other end 36 of the resistance element is clamped between the contact 30 on the other screw and the base of its recess 31. Thus, it will be evident that current will flow from the line to which the conductors 18, 18a are connected, through the resistance wire 35 and back to the line, while passing through the internally tapered socket members 14 and the externally tapered contacts 30.

50 In assembling my improved connector construction, the contacts 30 are disposed in registry with the sockets in the socket members 14, with the threaded member 22 extending up through the axial aperture 21 in the insulating member 1, whereupon, the contacts 30 having previously been correctly adjusted by the screws 32, by simply tightening the adjusting nut 23, the contacts 30 will be drawn into the tapered sockets in the socket members 14, in such manner as to provide effective contact therewith. When the internally and externally tapered surfaces of the parts are thus in contact, it will be evident that a uniform and continuous contact is provided not only around the axis of the parts, but 65 longitudinally of the latter for a substantial distance, all in such manner as to insure an obviously highly advantageous electrical connection between the parts. Further, it will be evident that the integral sleeve type tapered sockets and contacts thus provided, are of a character well adapted to withstand the intense heat generated by the resistance element 35, without sticking. Also, as a result of the tapers provided, the contacts 30 may be moved, as desired, closer together 70 or reversely to disengage the tapered socket

members 14, by a suitable operation of the adjusting nut 23 which, when adjusted, causes the heating unit 3 to move relative to the base 1.

As a result of my improved construction, it has been found practical to utilize heating units of 5 very high wattage, for example, up to a wattage of 2000, without the connector means, including the cooperating tapered socket members and tapered contacts, showing any objectionable effects from this high temperature. Further, it is 10 found that contact means of my improved construction stand up under long continued service and continue to function satisfactorily electrically, without any evidence of deterioration or sticking, under conditions which are impossible 15 with connectors of previous constructions. Moreover, even after long continued service, the contacts are readily separated whenever desired, as, for example, to permit the substitution of a heating unit, by a mere ready and quick ad- 20 justment of the adjusting nut. These and other advantages of my improved construction will, however, be clearly apparent to those skilled in the art.

While I have in this application specifically 25 described one form which my invention may assume in practice, it will be understood that the same is shown for purposes of illustration, and that my invention may be modified and embodied in various other forms without depart- 30 ing from its spirit or the scope of the appended claims.

What I claim as new and desire to secure by Letters Patent is:

1. In combination, a support, an insulating 35 base thereon, a heating unit having an insulating base coaxially disposed below and spaced from said first mentioned base, a plurality of co- 40 operating current conducting sockets and contacts bridging the space between said bases, said 45 sockets being carried by said first mentioned base and said contacts being carried by said second mentioned base, and means operable from the top of said support and above said first mentioned base for drawing said bases together and forcing said sockets and contacts longitudinally into good current conducting relation.

2. In combination, a support, an insulating base thereon, a heating unit having an insulating base coaxially disposed below and spaced from 50 said first mentioned base, a plurality of cooper- 55 ating sockets and contacts carried by confront- 60 ing portions on said bases, said sockets having elongated tapered contact surfaces and being mounted in recesses in said first mentioned base 65 and said contacts having correspondingly elongated tapered surfaces projecting above said sec- 70 ond mentioned base and bridging the space be- 75 tween said bases, and means connected to said second mentioned base and extending through said first mentioned base and said support and 80 operable from above the latter for drawing said bases together and forcing said sockets and contacts longitudinally into current conducting relation.

3. In combination, a support, an insulating base thereon, a hollow heating unit having an insulating base coaxially disposed below and spaced from said first mentioned base, cooperat- 70 ing sockets and contacts carried by said bases 75 and bridging the space therebetween, said sockets being disposed in recesses in said first men- 80 tioned base and having inner elongated tapered contact surfaces, and said cooperating contacts being carried by said second mentioned base and 85

having elongated tapered outer contact surfaces adapted to engage the corresponding tapered surfaces of said sockets throughout a substantial length, holding means for said contact means extended through said second mentioned base and threaded into the non-engaging ends of said contacts and adjustable from within the hollow body of said heating unit, and means extending axially of said bases and operable from above the first mentioned base for drawing said bases together and forcing said cooperating contact surfaces into good current conducting relation.

4. In combination, a support, an insulating base thereon, a heating unit having an insulating base disposed below said support so that said bases are disposed in the path of the rising heat, cooperating contacts carried on confronting portions of said bases, and axial connecting means for said bases including an element carried by the base of said heating unit and extending through said first mentioned base and said support and a cooperating element having a clamping connection with said first mentioned element and operable from the exterior of said support.

5. In combination, a support, an insulating base thereon, a heating unit having an insulating base disposed vertically below said base, cooperating tapered contact and socket means carried by confronting portions of said bases and holding said bases in spaced relation, and means for drawing said contact and socket means into operative relation having an element carried by said second mentioned base and a cooperating connecting and releasing element operative from the exterior of said support.

6. In combination, a support having an insulating base, a heating unit having an insulating base spaced vertically below said support, co-

operating tapered contacts and sockets carried by said bases and bridging the space therebetween on opposite sides of the axis of said support and unit, and an axial connection between said support and unit including means extending through said first mentioned base and support and into said second mentioned base for drawing said contacts and sockets into current conducting relation.

7. In combination, a support having an insulating base, a heating unit having an insulating base and disposed vertically below the base of said support, cooperating tapered contact and socket means carried by said bases, and means for drawing said contact and socket means into current conducting relation having cooperating connecting elements, one carried by the base of said heating unit and extending through said first mentioned base and said support and the other operable from the exterior of said support.

8. In combination, a support, a base carried thereon, a heating unit having a base and disposed coaxially with said first mentioned base, cooperating tapered socket and tapered contacts disposed on opposite sides of the axis of said bases and having the tapered surfaces of said contacts in engagement with the tapered surfaces of said sockets, and means carried by said heating unit and extending through said first mentioned base and said support and operable from the exterior of the latter for moving said tapered contacts relative to said tapered sockets, said last mentioned means being disposed coaxially of said first mentioned base and said heating unit and operable to permit movement of said tapered contacts in either direction relative to said tapered sockets.

FRANK E. WOLCOTT.
